UNITED STATES PATENT OFFICE.

BENJAMIN H. MARCUS, OF BROOKLYN, NEW YORK.

SNAP-FASTENER.

1,203,224.

Specification of Letters Patent. Patented Oct. 31, 1916.

Application filed October 14, 1915. Serial No. 55,795.

To all whom it may concern:

Be it known that I, BENJAMIN H. MARCUS, a citizen of the United States, residing at Brooklyn, in the county of Kings and State of New York, have invented certain new and useful Improvements in Snap-Fasteners, of which the following is a full, clear, and exact specification.

This invention relates to snap fasteners or separable buttons of the type having a solid head and a resilient socket.

It is the aim of the invention to produce a separable button of this kind which is very simple in construction and inexpensive to manufacture but which will effectively retain the parts of the button together when assembled and will not soon lose its holding power. In order to insure a better grip of the resilient socket upon the head, the gripping member is provided with three head engaging portions arranged equidistantly apart around the head, and the holding force of the gripping members is exerted in a direction parallel to the plane of the button and at right angles to the axis of the head.

The invention will be first hereinafter described in connection with the accompanying drawings, which constitutes a part of this specification, and then more specifically defined in the claim at the end of the description.

In the accompanying drawings, wherein similar reference characters are used to designate corresponding parts throughout the several views: Figure 1 is an inner face view of the socket member of a separable button or snap fastener constructed substantially in accordance with the present invention, a portion of the head of the button being shown in the socket. Fig. 2 is a transverse section on the line II-II of Fig. 1, the head carrying member of the device being shown in edge view. Fig. 3 is an outer face view of the socket member alone, the positions of the head engaging portions of the gripping member when the enlarged portion of said head is forced therethrough being indicated in dotted lines.

Referring more particularly to the drawings, 1 designates the socket member of the snap fastener or separable button. This member is made as a flat disk provided with a central opening 2 and having its edge turned or rolled to form a bead-like flange 3 on the outer face of the disk. The member

1 is also provided with a suitable number of perforations 4 for sewing said member to a garment.

The resilient socket member or head gripping device comprises a piece of wire 5 bent into generally triangular shape with three head engaging parts 6, 7 and 8 all arranged in the same plane. The parts 6 and 7 are connected by a sharp bend in the wire indicated at 9, while the parts 6 and 8 are similarly connected by a sharp bend 10. The other extremities of the parts 7 and 8 may be free or separated from one another, as indicated at 11 and 12. The resilient socket piece 5 is held in operative position by having the bends 9 and 10 and the free ends 11 and 12 underlie the flange 3 on the disk 1.

As illustrated best in Fig. 3, the bends 9 and 10 engage the peripheral wall of the flange 3, while the free ends 11 and 12 of the parts 7 and 8, respectively, of the resilient socket member, are normally spaced away from said peripheral wall of said flange. It will be observed that the parts 6, 7 and 8 are practically the same length so as to form what might be termed a triangle except that the sides or parts 6, 7 and 8 are bowed or curved inwardly to bring their middle portion into position to engage the head of the fastener. When the head, which is shown at 14 carried by a disk 13, is forced into the socket member, the part 6 will not yield to any appreciable extent because the extremities of said part at the bends 9 and 10 are in contact with the peripheral wall of the flange 3. These bends 9 and 10 may be held in this position by clamping the flange 3 more forcibly upon them than upon the free ends 11 and 12. It will thus be seen that in this form of the invention, substantially all of the yielding action is confined to the parts 7 and 8 which, as the enlarged end portion 14 of the head is forced through the socket member, will be spread apart or forced outward to the position indicated in dotted lines in Fig. 3. As soon as the head 14 has been entirely seated in the socket member, the parts 7 and 8 will spring inward to the solid line position in Fig. 3 and grip the reduced portion 15 of the head as shown in Figs. 1 and 2.

Having thus described my invention, what I claim as new, and desire to secure by Letters Patent is:

In a snap fastener, a socket piece having a turned over flange at its edge, and a grip-

ping member of resilient wire bent to generally triangular shape with its sides arranged in position to engage a head, the extremities of the sides at two corners of the triangle normally engaging the outer wall of the flange, and the extremities of two of the sides at the other corner of the tri-

angle being normally spaced away from the outer wall of the flange for the purpose specified.

10 In testimony whereof I have signed my name to this specification.

BENJAMIN H. MARCUS.
